UNITED STATES PATENT OFFICE.

HARRY B. TAYLOR, OF EAST ORANGE, NEW JERSEY, ASSIGNOR TO SEARLS MANUFACTURING COMPANY, OF NEWARK, NEW JERSEY, A CORPORATION OF NEW JERSEY.

DESIGN FOR A HOLDER FOR TUMBLERS OR OTHER ARTICLES.

40,931.

Specification for Design.

Patented Oct. 4, 1910.

Application filed June 29, 1910. Serial No. 569,604. Term of patent 7 years.

To all whom it may concern:

Be it known that I, HARRY B. TAYLOR, a citizen of the United States, residing at East Orange, county of Essex, State of New Jersey, have invented a new, original, and ornamental Design for a Holder for Tumblers or other Articles, of which the following is a specification, reference being had therein to the accompanying drawing, forming part thereof.

The figure is an elevation of a holder for a tumbler or other articles, showing my new design.

I claim:

The ornamental design for a holder for tumblers or other articles, as shown.

HARRY B. TAYLOR.
